THERMOSTATIC VALVE

Anthony J. Donohue, Philadelphia, Pa., assignor
to Simplex Gas Products Corporation, Phila-
delphia, Pa., a corporation of Delaware

Application February 16, 1932. Serial No. 593,339

12 Claims. (Cl. 137—139)

This invention relates to thermostatic valves, and more particularly to thermostatic valves operated through the medium of a thermostatic element of the type usually referred to as the Spencer disc.

5 An important object of the present invention is the provision in a valve of this character of an arrangement such that the valve proper may be moved through a distance considerably greater than the distance through which the thermostatic disc moves and maintained in such position without the use of levers or other intermediaries upon which wear would have any serious effects in the operation of the valve.

10 15 A further and more specific object of the invention is the provision in an apparatus of this character of means whereby a disc-type thermostat operating with a "snap" motion may exert its forces to toss a valve from its seat a distance greater than that through which the disc moves, together with means for latching the valve in its elevated position.

20 25 A further object of the invention is the provision in an apparatus of the character just described of a latching means so constructed that it may be released to effect a preparatory closing movement of the valve so that the valve is partially closed without a complete closure, and is locked to the thermostatic disc to be closed by the 30 reflex action thereof, thereby eliminating burner "pop" which would result were the closing action of the valve instantaneous.

35 These and other objects I attain by the construction shown in the accompanying drawings wherein, for the purpose of illustration, I have shown a preferred embodiment of my invention and wherein:

40 Fig. 1 is a side elevation partially in section showing a valve constructed in accordance with my invention employed to control the flow of gas and secondary air in a gas furnace;

45 Fig. 2 is a section on line 2—2 of Fig. 1;

Fig. 3 is a bottom plan view of the valve with the lower cover plate removed;

50 Fig. 4 is a front elevation, partially in section, of the valve;

Fig. 5 is an enlarged sectional view with the parts in the position which they occupy after initial operation of the heating element and prior 55 to operation of the thermostatic disc; and

Fig. 6 is a semi-diagrammatic view showing the electrical control connections for the valve.

Referring now more particularly to the drawings, the numeral 10 generally designates a valve casing having the usual partition 11 formed with

a seat 12 for a valve generally designated at 13. The casing has an opening 14 in alignment with the seat, this opening having a flange 15 receiving the flange 16 of an operating casing 17 containing mechanism through which the valve is actuated. The valve is equipped with a stem 18 projecting into the operating casing 17 and, preferably, sealed at its point of entrance in the operating casing by means of a diaphragm 19.

The operating casing 17 affords vertically spaced bearings 20 and 21 for guiding the valve stem 18 and below the lowermost bearing is disposed a flexed bimetallic disc 22 capable of moving with a snap from one to another of two positions upon a predetermined change in temperature. 70 This disc is secured at its edges in any suitable manner, being at present shown as confined by means of circular rim 23 having a groove 24 on its inner face for the reception of the outer edge of the disc. At the under surface of the disc a heating element 26 is disposed, which is adapted for connection with the thermostatic control circuit in the manner of the heating elements associated with the thermostatic disc disclosed in my prior application, Serial No. 382,144, filed July 30, 1929, for Thermostatic burner control.

Secured centrally to the disc 22 is a tubular guide 27 which guide has its lower end closed as indicated at 28 and its upper end open to receive the lower end of stem 18 which normally, by gravity, tends to rest upon the lower end 28 of the guide and is freely vertically movable in the guide. The guide has pivotally connected thereto a rocker 29 having a pair of latch arms 30 and 31 projecting toward the stem, the arm 30 operating through an opening 32 formed in the guide 27 and being equipped at its inner end with a roller 33. Arm 31 at its free end is provided with a latch piece having upwardly and downwardly facing shoulders 34 and 35 for co-action with the upper and lower ends respectively of a latch piece 36 carried by and disposed in a recess 37 formed in the stem 18. The arms are so proportioned that when the latch piece of arm 31 is withdrawn from the recess 37 roller 33 will be projected into the path of the lower end of the stem or against the side of the stem depending upon the position of the stem, disengagement of the latch piece of the arm from the latch piece 36 of the stem occurring at the time when the roller is engaged against the side of the stem should it be disposed in the path thereof.

A light spring 38 constantly urges rotation of the rocker about the pivot 39 thereof in a direction such that roller 33 110

constantly tends to project into the path of the stem or against the same.

Supported from the casing 17 through a bracket arm 40 is a bell crank lever 41 one arm of which has a roller 42 engaging the upper end of rocker 29 and the lower end of which has a depending arm portion 43 provided with an adjustable stop 44 arranged in the path of the free end of a bimetallic strip 45 which is likewise subjected to heat radiated by heating element 26 and which when cooled abuts the stop 44 elevating the associated arm of bell crank 41 and forcing roller 42 into engagement with the rocker 29 with sufficient force to overcome the action of spring 38 and cause the latch element to move toward and into engagement with the stem 18 of the latch piece 36 thereof.

Assuming that the parts are in the position shown in Fig. 5, which is the position which they will assume after energization of heating element 26 through a period sufficient to actuate bimetallic leaf 45 without effecting the actuation of disc 22, the flexing of leaf 45 has permitted the roller bearing arm of bell crank 41 to recede and thus permitted the rocker 42 to be actuated by its spring 38 to a position where the roller 33 is engaged against the surface of the stem 18, the lower end of stem 18 resting upon the closed end 28 of guide 27. A slight continued heating with the parts in this position will cause actuation of disc 22 which, moving with the characteristic movement of such discs, snaps upwardly imparting its motion to stem 18. Movement of the guide 27 being limited by its attachment to the disc, the stem 18 with its attached valve 13 continues to rise after movement of the guide has been checked so that the lower end of the stem is thrown above roller 33 and spring 38 acts to project the roller beneath the stem and thus prevent it against falling to the bottom of the guide 27 so that the parts are then in the position illustrated in Fig. 1. With the parts in this position, assuming that energization of heating elements 26 is discontinued, both the thermostatic disc 22 and leaf 45 begin to cool and since the latter is actuated more quickly, the leaf first acts to raise the stop 44 and thus force roller 42 into engagement with rocker 29 actuating the same to a position where the roller 33 releases the valve stem permitting the same to drop. It will be recalled that the disc at this time has its camber upwardly disposed so that the valve is held slightly off its seat when the stem has dropped into engagement with the closed bottom 28 of the guide 27. The shoulder 35 of the latch piece of arm 31 of the rocker engages over the upper end of the latch piece 36 of the stem so that the stem and guide are locked together. As the cooling action continues disc 22 is actuated, snapping to the position shown in Fig. 5, with the result that the valve stem is moved rapidly downwardly to the closed position of the valve. In order that regulation of the force of engagement of valve 13 with its seat may be had, the stem 18 is loosely directed through the valve and provided at its upper end with an adjustable head 46 confined in a pocket 46a formed in the upper portion of the valve. By adjustment of this head, regulation of the extent of engagement of the valve 13 may be had from no pressure to substantially the full pressure exertable by the disc.

In order that the valve may be manually actuated, when this is found necessary, I provide a lever 47 which extends through slots 48 and 49 formed in the actuator casing 17 and is pivoted

to the wall of the casing at one side thereof as indicated at 50 and to the valve stem as indicated at 51. One end of this lever is formed with a hand grip 52 while the opposite end thereof is adapted for connection as at 53 with a secondary air door 54 or other element to be actuated simultaneously with opening of the valve. I additionally provide rocker 29 with an extension arm 55 projecting through an opening 56 formed in the casing wall and through operation of which the rocker may be manipulated to disengage the latch element of arm 31 from the latch element 36 of the valve stem. Such disengagement having been accomplished, the lever 47 may be actuated to elevate the valve from its seat, at which time the arm 55 is released. Since the bell crank lever 41 is at this time operating to maintain the rocker 29 in position with its latch elements against the valve stem, the shoulder 34 of the latch element will, by its engagement beneath the latch element 36 of valve stem 18, maintain this valve stem in elevated position. If, with the parts in this position, the automatic action is restored and the action of the heating element initiated, the snap of the disc in response to heating will cause a sufficient up-throw of the valve to disengage the latch elements of arm 31 and stem 18 and permit the rocker to operate under the influence of its spring to a position where its roller 33 intercepts and supports the valve through its stem. Attention is directed to the fact that the lever 47 in addition to forming a means for manually operating the valve also serves as a means for preventing rotation of the valve stem. In order that rotation of sleeve guide 27 may be prevented this guide may be provided with a rod 57 operating through an opening in the spider 58 supporting the lower guide bearing 21 of the valve stem.

The heating element comprises an annular insulating base about which is wound a pair of heating resistances 26a and 27a, the resistance 27a including the resistance 26a, as more clearly shown in the semi-diagrammatic Fig. 6 and being shunted by a switch comprising spring blades B and B' tending to disengage contacts carried thereby through their own resiliency. The upper blade is disposed in the path of the lower end of the guide fastening and, when the disc is downwardly convexed, is engaged by an insulating contactor C carried by this guide fastening and urged into engagement with the lower blade B', thus closing the circuit and shunting out the excess portion of the resistance leaving only the resistance 26a. It will be noted that this arrangement is identical with that suggested in my prior application, insofar as the substitution of heating resistances is concerned, the present arrangement having merely been adopted because it permits of direct operation of the switch by the thermostatic element and admits of a more compact arrangement of the switch than could otherwise be provided.

As the construction hereinbefore set forth is obviously capable of a considerable range of change and modification without in any manner departing from the spirit of my invention, I do not wish to be understood as limiting myself thereto except as hereinafter claimed.

I claim:

1. A valve assembly comprising a valve, a seat therefor, an element moving with a snap from one to another of two positions in one of which the valve is operatively engaged therewith, means for causing movement of the element, means for

- applying the energy released by the element in its movement from said position to the other of its positions to toss the valve from its seat a distance greater than the distance through which the element moves, a catch carried by said element for preventing return of the valve to its seat, and means for releasing the catch while the element is still in said other position to thereby permit a partial return of the valve to its seat which is checked by engagement of the valve with the element. 5 80
2. A valve assembly comprising a valve, a seat therefor, an element moving with a snap from one to another of two positions in one of which the valve is operatively engaged therewith, means for causing movement of the element, means for applying the energy released by the element in its movement from said position to the other of its positions to toss the valve from its seat a distance greater than the distance through which the element moves, means for preventing return of the valve to its seat, means for releasing the catch while the element is still in said other position to thereby permit a partial return of the valve to its seat which is checked by engagement of the valve with the element, and means for latching the valve to the element prior to its return to its original position. 10 85
3. A valve assembly comprising a valve, a seat therefor, an element moving with a snap from one to another of two positions in one of which the valve is operatively engaged therewith, means for causing movement of the element, means for applying the energy released by the element in its movement from said position to the other of its positions to toss the valve from its seat a distance greater than the distance through which the element moves, a catch carried by said element for preventing return of the valve to its seat, means for releasing the catch while the element is still in said other position to thereby permit a partial return of the valve to its seat which is checked by engagement of the valve with the element, and means for latching the valve to the element prior to its return to its original position. 15 90
4. A thermostatic valve assembly comprising a valve, a seat therefor, a thermostatic element moving with a snap from one to another of two positions as its temperature is raised or lowered, said valve being operatively engaged with the element when the element is in one of said positions, and means for applying energy released by the element in its movement from said position to the other position to toss the valve from its seated position a distance greater than the distance through which the element moves. 20 95
5. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, and means for preventing return of the valve to its seat. 25 100
6. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, a thermostatically-operated catch for preventing return of the valve to its seat, and a common heating means for controlling operation of the thermostatic element and latch. 30 105
7. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, a catch carried by the thermostatic element and engaging the valve to prevent its return to its seat. 35 110
8. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, a catch carried by the thermostatic element and engaging the valve to prevent its return to its seat, means for releasing the catch while the element is still in said other position to thereby permit a partial return of the valve to its seat which is checked by engagement of the valve with the element, and means for latching the valve to the element prior to its return to its original position. 40 115
9. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, and a thermostatically-operated means for preventing return of the valve to its seat. 45 120
10. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, a thermostatically-operated catch for preventing return of the valve to its seat, and a common heating means for controlling operation of the thermostatic element and latch. 50 125
11. A thermostatic valve assembly comprising a valve, a seat therefor, a thermostatic element moving with a snap from one to another of two positions as its temperature is raised or lowered, said valve being operatively engaged with the element when the element is in one of said positions, means for applying energy released by the element in its movement from said position to the other position to toss the valve from its seated position a distance greater than the distance through which the element moves, a catch carried by the thermostatic element and engaging the valve to prevent its return to its seat. 55 130

- positions as its temperature is raised or lowered, said valve being operatively engaged with the element when the element is in one of said positions, means for applying energy released by the element in its movement from said position to the other position to toss the valve from its seated position a distance greater than the distance through which the element moves, a catch carried by the thermostatic element and engaging the valve to prevent its return to its seat, means for releasing the catch while the element is still in said other position to thereby permit a partial return of the valve to its seat which is checked by engagement of the valve with the element, means for latching the valve to the element prior to its return to its original position, and a thermostat controlling operation of said catch and latching means.
12. A thermostatic valve assembly comprising a valve, a seat therefor, a thermostatic element moving with a snap from one to another of two

positions as its temperature is raised or lowered, said valve being operatively engaged with the element when the element is in one of said positions, means for applying energy released by the element in its movement from said position to the other position to toss the valve from its seated position a distance greater than the distance through which the element moves, a catch carried by the thermostatic element and engaging the valve to prevent its return to its seat, means for releasing the catch while the element is still in said other position to thereby permit a partial return of the valve to its seat which is checked by engagement of the valve with the element, means for latching the valve to the element prior to its return to its original position, a thermostat controlling operation of said catch and latching means, and a single heating means controlling operation of said thermostats.
